U. STEINER

GRINDING MACHINE

Filed May 16, 1924

Inventor:
Ulrich Steiner.

John B. Bragg
M. D. 'y.

UNITED STATES PATENT OFFICE.

ULRICH STEINER, OF LIMA, OHIO, ASSIGNOR TO LANDIS TOOL COMPANY, OF WAYNESBORO, PENNSYLVANIA, A CORPORATION OF PENNSYLVANIA.

GRINDING MACHINE.

Original application filed December 7, 1920, Serial No. 428,951. Divided and this application filed May 16, 1924. Serial No. 713,866.

My said invention relates to grinding machines and specifically to the mechanism for imparting a rotating and reciprocating movement to the grinder shaft of a grinding machine. The main object of the invention is to provide a device of the character indicated which shall be accurate and reliable and which may be adjusted to vary the position of the stroke of the grinding wheel.

10 This application is a division of my application No. 428,951, filed December 7, 1920.

Referring to the accompanying drawings, which are made a part hereof and on which similar reference characters indicate similar parts,

Figure 1 is an elevation of the mechanism for traversing the grinding wheel shaft,

Figure 2 a vertical section of the traversing mechanism on line 2-2 of Figure 1, and

Figure 3 a vertical section on line 3-3 of Figure 1 with certain parts omitted.

In the drawings of the parent application above referred to there is shown a fixed frame on which the parts of the machine are supported. A worktable on this frame supports the device to be operated on by the grinding wheel 27 or other abrading means. The grinding wheel may be operated by a pulley connected in a suitable source of power and mounted on a grinding wheel shaft 29 rotating in bearings on standards at the ends of the frame one of said standards being shown at 30 in Figure 1. The grinding wheel shaft in addition to this rotary movement may have a movement of rotation.

The standard 30 of the frame contains one of the bearings for shaft 29 and also has integral therewith a projecting collar 30' to which is fixed, as by means of screw threads, a housing 32 for the projecting end of spindle 29 which comprises a reduced portion 33, a second reduced portion 34, and a third reduced portion 35 provided at its outer end with a worm 36.

The portion 35 is screw threaded adjacent portion 34 of the shaft and carries a nut 37 which holds a yoke 38 in place on the portion 34, said yoke being here shown as consisting of a ring or collar with fingers 39.

Rotation of this yoke is prevented by engagement of a pair of the fingers 39 thereon with a squared portion 40 of a rod 41 secured in a casing 42. This casing surrounds the housing 32 and is free to move thereon in a longitudinal direction. Worm 36 engages a worm wheel 43 loosely mounted on a transverse shaft 44 journaled at its ends in bearings 45 on casing 42. This shaft carries a conical member 46 at one end, this member engaging a socket 47 of one of the bearings 45, and has between its ends a pair of eccentrics 48 and a cone member 49 for engagement with a cup member 50 on the worm wheel. The cone is keyed to the shaft at 51 and has operating means comprising a rod 52 with a hand wheel 53 thereon said rod being threaded at 54 to a sleeve fixed in the bearing 45. This rod at its inner end passes through a bore of shaft 44 and engages the key 51 to move the cone 49 into driving engagement with the worm wheel. When the shaft 44 is thus driven eccentrics 48 operate levers 55 pivoted at 56 and connected at their further ends to links 57. These links are adapted to move the yokes 38 by engagement with pins 58 projecting from said yokes and it will be seen that on rotation of the shaft 29 the worm 36 will act, if the clutch members 49 and 50 are in engagement with each other, through the worm wheel and its shaft 44 to slide the yoke back and forth in the housing 32, thus moving the shaft 29 longitudinally of itself and also moving the grinding wheel to avoid scoring of the work, as above set forth. If the clutch members are disengaged the worm wheel 43 will merely ride loosely on shaft 44.

The casing 42 is held against rotation by engagement of a lug 59 thereon with a finger 60 projecting from the standard 30, but it is adapted to slide longitudinally of the housing, the engagement between the members 59 and 60 and between the rod 41 and connected parts permitting such movement. This capacity for movement is given to the casing to permit adjustment of the position of the stroke of the grinding wheel and the adjusting means comprises a shaft 61 with a hand wheel 62 for moving the friction device 63 into and out of engagement with

2
a segment 64 fast to a sleeve 65 which is driven into an opening at the top of casing 42. A bracket 66 holds the rod 61 and is fixed to a shaft 67 journaled in sleeve 65, this shaft having at its lower end an eccentric pin 68. This pin engages an opening in a block 69 located in an annular groove 70 of housing 32. It will be seen that rotation of shaft 67 will move the casing 42 and the parts carried by the casing toward and from standard 30 and will thus change the longitudinal position of shaft 29 and the throw of the grinding wheel.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent is:

1. In a grinding machine, a rotary grinding wheel and its shaft, means driven from the shaft to move the same reciprocatingly comprising a casing, gearing in the casing connected to the shaft, and means to adjust the casing in the direction of the axis of the shaft thereby varying the position of the reciprocating stroke, substantially as set forth.

2. In a grinding machine, a rotary grinding wheel and its shaft, a fixed housing about the shaft, a casing surrounding the same, means carried by the casing to move the shaft reciprocatingly, and means to adjust the casing longitudinally of the housing, whereby the position of the extremes of movement of the shaft is varied, substantially as set forth.

3. In a grinding machine, a rotary grinding wheel and its shaft, means for imparting reciprocating movement to the grinding wheel comprising a worm on a reduced portion of the shaft, a yoke in engagement with the shaft, means to prevent rotation of the yoke, a worm wheel in engagement with the worm, such worm wheel being mounted on a shaft extending transversely of the grinding wheel shaft, eccentrics on the transverse shaft and connections from the eccentrics to the yoke for moving the yoke and the grinding wheel shaft reciprocatingly, substantially as set forth.

4. In a grinding machine, a rotary grinding wheel and its shaft, means for imparting reciprocating movement to the grinding wheel comprising a housing on the fixed frame of the machine surrounding the grinding wheel shaft, a casing loosely mounted thereon, means to hold said casing against rotation, a yoke connected to the shaft, a shaft in said casing extending transversely of the grinding wheel shaft,

connections between the said shaft and the yoke, and means to adjust the casing on the housing longitudinally of the grinding wheel shaft whereby the grinding wheel shaft is adjusted in a longitudinal direction, substantially as set forth.

5. In a grinding machine, a grinding wheel shaft, a transverse shaft having one or more eccentric parts, gearing connecting said shafts, a yoke on the grinding wheel shaft, and means connecting said eccentric portions to said yoke for reciprocating said grinding wheel shaft as it rotates, substantially as set forth.

6. In a grinding machine, a grinding wheel shaft, a transverse shaft, gearing connecting said shafts for driving one from the other, a yoke on the grinding wheel shaft, and connections from the yoke to the transverse shaft for moving the grinding wheel shaft axially as it rotates substantially as set forth.

7. In a grinding machine, a grinding wheel shaft, a transverse shaft, gearing connecting said shafts, a yoke on the grinding wheel shaft, and connections from the yoke to the transverse shaft for moving the grinding wheel shaft axially as it revolves said connections including a clutch and means for disengaging the parts thereof, substantially as set forth.

8. In a grinding machine, a rotary grinding wheel shaft, a worm on the shaft, a yoke in engagement with the shaft, a shaft extending transversely of the grinding wheel shaft, a worm wheel on the latter shaft engaging said worm, eccentrics on the transverse shaft, and connections from the eccentrics to the yoke for moving the yoke and the grinding wheel shaft reciprocatingly, substantially as set forth.

9. The combination of a grinding wheel shaft, a second shaft extending transversely of the first, connections between said shafts for driving the second shaft, connections from the second shaft to the first for reciprocating the first shaft, and means for disabling the connections from the second shaft to the first, substantially as set forth.

10. In a grinding machine, a rotary grinding wheel shaft, a worm on the shaft, a yoke in engagement with the shaft, a shaft extending transversely of the grinding wheel shaft, a worm wheel thereon engaging said worm, eccentrics on the transverse shaft, and connections from the eccentrics to the yoke for moving the yoke and the grinding wheel shaft reciprocatingly, substantially as set forth.

11. The combination of a grinding wheel shaft, a bearing near one end thereof, a housing fixed to the bearing and surrounding the shaft, a casing about the fixed housing, a shaft extending transversely of the first, connections between said first and sec-

ond shafts for driving the latter, connections from the second shaft to the first for reciprocating the first shaft, connections between the housing and the casing for adjusting the casing lengthwise of the housing, and connections between the casing and the

axially with the casing, substantially as set forth.

In witness whereof, I have hereunto set my hand and seal at Lima, Ohio, this eighteenth day of April, A. D. nineteen hundred and twenty-four.

ULRICH STEINER. [L. S.]
